RADIO RECEIVING SYSTEM

Ben J. Chromy, Hopkins, Minn.

Application April 16, 1930. Serial No. 444,836

7 Claims. (Cl. 250—11)

This invention relates broadly to radio receiving systems. More specifically this invention relates to radio receiving systems arranged to intercept signaling energy for the operation of frequency selective indicators.

An object of this invention is to provide an arrangement wherein signaling energy intercepted by a receiving system is impressed upon one or more electro-mechanically vibratile elements for the energization thereof.

Another object of this invention is to provide an arrangement wherein signaling energy intercepted by a receiving system is impressed upon a plurality of electro-mechanically vibratile elements, each having a different frequency characteristic, for the energization of selected ones thereof when signaling energy of the proper frequency is intercepted by the receiving system.

Still another object of this invention is to provide an arrangement wherein signaling energy intercepted by a receiving system is impressed upon one or more piezo-electric crystals which are caused to glow when the signaling energy intercepted is of the proper frequency.

Other features and objects of this invention will be readily apparent to those skilled in the art to which this invention is related from the following specification and the appended claims.

This invention is related to radio receiving systems disclosed in my copending applications Serial Numbers 433,912 and 443,564, filed March 7, 1930, and April 11, 1930, respectively. In accordance with this invention signaling energy transmitted from a radio beacon located at an aircraft landing field or similar port is intercepted by the antenna of the receiving system located on board the moving vessel which is being directed or guided to the field or port. The signaling energy, after being amplified to a sufficient degree, is impressed upon electro-mechanically vibratile elements, such as piezo-electric crystals. These crystals are positioned in vessels containing rarefied inert gas, such as neon, helium, krypton or mixtures of inert gases. In those arrangements of this invention where two piezo-electric crystals are employed, specimens of crystals having frequency characteristics substantially alike but displaced in the frequency spectrum by about one kilocycle are selected. Crystals having frequency characteristics spaced by more or less than one kilocycle may be conveniently used, if desired; in cases where this system is employed on the shorter wave lengths it may be desirable to use crystals spaced by less

than one kilocycle in order to keep interference to other signal transmissions at a minimum.

The signaling energy transmitted from the beacon corresponds in frequency to the frequencies of the piezo-electric crystals employed in the system aboard the moving craft. The beacon transmitter may be arranged to transmit signaling energy in beams radially from it. Alternate ones of these beams may be of slightly different frequency; that is, corresponding in frequency to the frequencies of the piezo-electric crystals.

The details of this invention will be more readily understood from the drawings, in which:

Fig. 1 illustrates an embodiment of this invention;

Fig. 2 illustrates a modified form thereof;

Fig. 3 shows graphically the manner in which beams of signaling energy are radiated from the radio beacon;

Fig. 4 illustrates a top plan view of the piezo-electric crystal mounting;

Fig. 5 is a view in side elevation of the piezo-electric crystal mounting;

Fig. 6 is a detail view of the electrode employed with the crystal, and

Fig. 7 shows a modified form of piezo-electric crystal mounting.

Referring to Fig. 1 in detail, reference numeral 1 designates a directional antenna of the loop type. Antenna 2 is coupled to the circuit of antenna 1 thru the transformer 3 for the purpose of feeding signaling energy of the proper phase relation upon the circuit of antenna 1 and thereby give the whole antenna array the desired cardioidal field strength characteristic. The coupling between the windings of the transformer 3 may be varied until the proper energy transfer takes place between the circuit of antenna 2 and the antenna 1. The condenser 5 is employed to adjust the period of the loop antenna. The condenser 4 is connected into the circuit of antenna 2 for the purpose of providing a frequency adjusting means therefor. Inductance 6 is connected between the loop antenna and the tuned circuit comprising inductance 8 and condenser 7. Inductances 9 and 10 are shunted by variable condensers 11 and 12 and are also variably coupled to the inductance 8. One of the inductances 9 and 10 may be eliminated in cases where piezo-electric crystals 24 and 25 which are connected into the output circuit of electron discharge device 18 have frequency characteristics not widely separated. In cases where these crystals have frequency characteristics differing substantially, that is, by more than five kilocycles from each

other, it is advantageous to employ two secondary coils 9 and 10 separately tuned. It is, of course, understood that the secondary of the coupling transformer 15, which couples the high frequency amplifier 16 to the electron discharge device 13, may also be in two sections separately tuned. The transformer 17 is connected to couple the amplifier 16 to the electron discharge device 18. This latter transformer may be designed 10 to be sufficiently aperiodic so that the desired high frequency signals are efficiently transmitted by it to the electron discharge device 18, or it likewise may be provided with two separately tuned secondary windings.

15 The piezo-electric crystals 24 and 25 are mounted in the envelope 23, which is of glass or other similar transparent material. Each of the crystals is positioned in a separate compartment. This, however, is not essential, since they may 20 both be in the same compartment, although it is desirable, because in operation it may be desirable to fill the compartment of one crystal with an atmosphere of rarefied neon gas or some other inert gas or mixture of inert gases, while it may 25 be desirable to fill the other compartment with some such gas as helium or argon at a low pressure.

The crystals 24 and 25 are connected in parallel across the choke coil 20 and the condenser 30 19. The dimensions of the coil 20, the condenser 19 and the piezo-electric crystal holders are preferably such as to cause the circuits of these crystals to be resonant to frequencies corresponding substantially to the frequencies of the 35 crystals. The choke coil 20 is, therefore, preferably of large inductance as compared to its distributed capacity. This choke coil may be made up of several honeycomb coils arranged in spaced relation.

40 By-pass condenser 22 is connected across the source of current supply 21. Source of current supply 14 is connected into the anode circuit of device 13.

In operation the radio beacon sending out 45 signaling energy for the guiding of moving craft to the port is arranged to send out at least two beams, as shown in Fig. 3.

Zone A of one of the beams is of one frequency, for example, 3,000 kilocycles, while zone B is a 50 beam of another frequency, for example, 3,005 kilocycles, and zone C is a beam of both of these frequencies. Zone C consists of those portions of the two beams transmitted from the beacon which overlap. When the aircraft or similar vessel which is being guided into the airport is traveling in zone A, then signaling energy of, for example, 3,000 kilocycles being intercepted and impressed upon the circuits of the piezo-electric crystals 24 and 25, and that crystal which has a 55 fundamental frequency of 3,000 kilocycles will be energized, whereupon the rarefied atmosphere of inert gas surrounding it will be caused to glow. If the aircraft is proceeding in the zone B in which the 3,005 kilocycle signal is being transmitted, then the other piezo-electric crystal, that is, the one having a fundamental frequency of 3,005 kilocycles, will be energized and the rarefied inert gas atmosphere surrounding it will be caused to glow. When, however, the aircraft 70 is in the zone C in which signals of both frequencies are being transmitted both crystals will be energized and the gases surrounding both of them will glow. The operator of the craft will then be informed of the fact that the craft is 75 proceeding toward the beacon.

In Fig. 2 a modified form of this invention in which two antenna arrays consisting of loops 27 and non-directional antenna 26 and loop 33 and non-directional antenna 32, respectively, are coupled to the input circuits of separate amplifier systems. The antenna 26 having a tuning condenser 30 and a coupling transformer 28 associated therewith is coupled by means of the transformer 28 to the circuit of loop 27. A tuning condenser 29 is provided as a means for adjusting the period of the loop 27. The input circuit of the electron discharge device 31 is connected to the circuit of the loop 27. The electron discharge device 37 is connected across the tuning condenser 35 which is employed for adjusting the period of the loop 33. Coupling transformer 34 is provided for coupling the circuits of the antenna 32 and the loop 33. A tuning condenser 36 is connected into the circuit of antenna 32. A source of anode current supply 38 is connected to the electron discharge devices 31 and 37. Transformers 39 and 40 are connected into the anode circuits of the devices 31 and 37, respectively, for coupling the circuits thereof to the amplifiers 41 and 42, respectively. Transformers 43 and 44 100 are employed to couple the electron discharge devices 45 and 46 to the output circuits of the amplifiers 41 and 42, respectively. Source of current supply 47 is connected to the devices 45 and 46. The choke coils 48 and 49 are similar to the choke coil 20 of Fig. 1. These coils are connected to the anodes of the devices 45 and 46. Condensers 50 and 51 are connected in series with the piezo-electric crystals 53 and 54, respectively. The crystal 53 is arranged to be energized by energy 110 from the device 45 and the crystal 54 from the device 46. This arrangement for energizing the crystals may be employed in the form of this invention illustrated in Fig. 1, in which case the secondary windings of transformers 43 and 44 115 would both be coupled to the primary of transformer 17. A transparent envelope 52 is provided for the crystals 53 and 54.

The operation of the arrangement of this invention illustrated in Fig. 2 is similar to that form 120 illustrated in Fig. 1, except that the signaling energies of different frequencies are intercepted by different antenna arrays and are separately amplified.

In Fig. 4 a top plan view of one of the piezo-electric crystal indicators is illustrated. A piezo-electric crystal 66 is mounted within the transparent envelope 69 in an atmosphere of rarefied neon, helium or similar inert gas or mixture of inert gases.

The crystal 66 is mounted upon a flat plate 66a, as illustrated in Fig. 5. Projecting members 67a and 67c, illustrated in Figs. 5 and 6, are provided to the plate 66a. These projecting members are positioned on the edges of the plate to retain the 130 crystal in position.

A screen electrode 65 is positioned upon the exposed face of the crystal. This electrode 65 is preferably in the form of a metallic mesh, in order that the glowing gas immediately adjacent 140 to the crystal during the energization of the latter is more readily visible. This screen electrode is held in position by the resilient members 68 which are provided with coil sections 68a to increase the resiliency thereof and cause the screen 145 electrode to contact with the upper face of the crystal. Members 68 are attached to the supporting members 64, which in turn are attached to the supports 68b. A tubular member 69 is provided about the stem 70. The supports 68b are at- 150

tached to this tubular member 70. Springs 67 are attached to the projecting members 67a and, together with the supporting members 61, which are attached to the member 66b, illustrated in Fig. 5, serve to support the crystal upon the stem 70. A base 71 is provided to the envelope 60. This base is arranged to fit into a socket in such a manner that prongs 71a contact with contacts of the socket. The plate 66a and the screen 65 are connected to the prongs 71a. The screen electrode 65 may be slightly displaced from the face of the crystal in cases where a more sensitive indicator is desired, and in those cases the members 68 are maintained in contact with the crystal in order to hold it in place. Where it is desired even the members 68 may be displaced from the surfaces of the crystal and small glass beads fastened to these members may be provided to engage the crystal surface.

In Fig. 7 a simplified piezo-electric crystal indicator is shown. In this form of indicator the crystal 77 is mounted in the vessel 72 of rarefied inert gas between the contact plates 76 which are connected by means of the wires 75 to the prongs 73a. The crystal, together with the plates 76, is supported by the wires 75 upon the stem 74. A base 73 is provided for retaining the indicator device in a suitable socket.

While several embodiments of this invention have been illustrated and described in considerable detail, it is, of course, to be understood that I do not desire to limit this invention to those details as set forth except in so far as they may be defined by the appended claims.

What I claim and desire to secure by Letters Patent of the United States is as follows:

1. In course finders adapted to be carried by aircraft the combination of an antenna system, signal receiving and amplifying means, indicating means including a pair of electro-mechanically vibratile elements connected to said signal receiving and amplifying means, said elements being resonant to slightly different radio frequencies, and means for exciting said elements at carrier frequencies transmitted from a ground station.

2. In course finders adapted to be carried by aircraft the combination of an antenna system, signal receiving and amplifying means connected to be energized by signaling energy intercepted by said antenna system, a pair of electro-mechanically vibratile elements resonant to slightly different radio frequencies connected to the output circuit of said amplifying means and means for exciting said elements at carrier signaling frequencies transmitted from a ground station.

3. In course finders for aircraft the combination of a plurality of electro-mechanically vibratile elements carried by said aircraft, each of said

elements being adjusted to resonate at a slightly different frequency, signal transmitting means for transmitting signaling energy having carrier frequencies corresponding to each of the resonant frequencies of said elements and signal receiving and amplifying means for intercepting and amplifying signals from said transmitting means for energizing said elements in accordance with said signaling energy.

80

4. In course finders for aircraft the combination of a directional antenna system, signal receiving and amplifying means connected to be energized by signaling energy intercepted by said antenna system and a pair of piezo electric crystals connected to the output of said amplifying means, said piezo electric crystals being ground to resonate at slightly displaced radio frequencies.

85

5. In course finders for aircraft the combination of a directional antenna system, signal receiving and high frequency amplifying means connected to be energized by signaling energy intercepted by said antenna system, a pair of piezo electric crystals connected to said amplifying means, said piezo electric crystals being ground to resonate at slightly displaced radio frequencies.

90

6. In course finders for aircraft the combination of a directional antenna, electron discharge device amplifying means having input and output circuits, means for coupling said antenna to the input circuit of said amplifying means, a pair of vibratory members adapted to be energized at radio frequencies, said vibratory members being adjusted to resonate at slightly different radio frequencies, means for impressing high frequency signaling energy upon said vibratory members, connections between said last mentioned means and the output circuit of said amplifying means and glow discharge means arranged to be energized when said vibratory members are energized by signaling energy transmitted from a ground station.

95

7. In course finders for aircraft the combination of a directional antenna, electron discharge device amplifying means having input and output circuits, means for coupling said antenna to the input circuit of said amplifying means, a pair of piezo electric crystals, said crystals being ground to resonate at slightly different radio frequencies, means for impressing high frequency signaling energy upon said piezo electric crystals, connections between said last mentioned means and the output circuit of said amplifying means, and glow discharge means arranged to be energized when said piezo electric crystals are energized by signaling energy transmitted from a ground station.
